TELEMETERING SYSTEM AND APPARATUS

Clyde E. Stewart, Upper Darby, Pa., assignor to
General Electric Company, a corporation of
New York

Application September 10, 1936, Serial No. 100,151

8 Claims. (Cl. 177—351)

My invention relates to telemetering apparatus and its use in a telemetering system and its object is to provide simple but reliable apparatus of this class which is applicable to a wide variety of uses.

In carrying my invention into effect in its preferred form, I employ a transmitter for opening and closing the telemetering circuit intermittently and vary the ratio of the time the circuit is open to the time it is closed in response to variations in the condition or measurement to be transmitted. At the receiving station, a relay is provided for alternately energizing a differential measuring system such as opposed thermocouple heater circuits in accordance with circuit-open and circuit-closed periods of the transmitter. These thermocouples then energize an instrument calibrated in terms of the condition or measurement thus transmitted.

The features of my invention which are believed to be novel and patentable will be pointed out in the claims appended hereto. For a better understanding of my invention, reference is made in the following description to the accompanying drawing wherein Fig. 1 illustrates a complete telemetering system according to the present invention; Figs. 2 and 3 show side and plan views of a transmitter for transmitting impulses indicative of water level; and Fig. 4 shows a system arranged for transmitting a plurality of different indications to a plurality of different points.

In Figure 1, a transmitter-commutating disk 10 is shown connected to the telemetering circuit 11 which runs to a relay 12 at a distant receiving station. 13 indicates a source of supply for the relay telemetering circuit and also for the circuit of two heaters 14 and 15 which are alternately energized by relay 12 through stationary contacts 16 and 17 of the relay and its movable contact 18. 19 indicates a variable resistance which may be omitted in case a substantially constant voltage source of supply is available at 13. The heater circuits are completed by a common wire 20. Closely associated with the heaters 14 and 15 are thermocouples 21 and 22 and these thermocouples are respectively connected to the opposing coils 23 and 24 of a differential millivoltmeter 25. The relay 12, the source of supply 13, heaters 14 and 15, the thermocouples, and the millivoltmeter 25 will be located at the receiving station.

The commutator disk 10 at the transmitting station is rotated at a uniform speed. It is provided with a conducting surface 26 over one half of its periphery and with an insulating surface 27 over the other half of its periphery. The con-

ducting portion 26 is electrically connected to the shaft 28 on which bears a brush 29 connected to one side of the telemetering circuit 11. Bearing on the periphery of the disk is a brush 30 which in most cases will be stationary and a brush 31 which may be adjusted from brush 30 about the periphery, approximately 180 degrees. Brushes 30 and 31 are connected together by wire 32 and to the other side of the telemetering circuit 11. The direction of rotation of the disk 10 is immaterial. Its rate of rotation may be one revolution per second more or less as long as it is constant.

It will now be evident that, when brush 31 is moved around to the same point occupied by stationary brush 30, the telemetering circuit 11 will be closed for one-half revolution of the disk when the conducting portion 26 is passing under the brushes and will be open for the other half of a revolution while the insulating part 27 is passing under the brushes. Thus, under such conditions, relay 12 will be energized for a half second and deenergized for the next half second and so on, or, in other words, it will be energized exactly one half the time. Consequently, heater 14 will be energized intermittently when the relay is energized for half the time and heater 15 will be intermittently energized when the relay is deenergized for the remainder of the time from the same source 13 and, consequently, the average heating effects on thermocouples 21 and 22 will be equal, the voltages produced thereby will be equal and opposite, and the differential millivoltmeter 25 will read zero. Calibrating resistances 33 and 34 may be provided in the heater circuits, if necessary, to equalize any unbalance in the calibration under these circumstances.

If now we move adjustable contact 31 away from stationary contact 30 about the periphery of the disk, the time during which relay 12 is energized will increase and the time during which it is deenergized will decrease during each revolution of the disk. This is because the brushes are in parallel. The effect is the same as if we had only one brush of varying width such as to span the arc between the two brushes 30 and 31.

If we move brush 31 around 90 degrees to the position indicated in the drawing, the relay telemetering circuit will be closed three-fourths of the time since it takes three-fourths of a revolution of the disk to move the conducting segment 26 past both brushes 30 and 31. For instance, if the disk rotates clockwise from the position shown, brush 30 will remain in contact with conducting segment 26 for one-half revolution but,

when the disk has made one-fourth revolution, brush 31 will engage the conducting segment 26 and then remain in contact for one-half revolution so that contact is made at one point or the other for three-fourths of a revolution.

If we move brush 31 around to the 180 degree point from brush 30, brush 30 will break contact with segment 26 at the same instant brush 31 makes contact therewith so that the telemetering relay circuit 11 will be closed continuously under such conditions. When this happens, heater 14 at the receiving station will be energized continuously and heater 15 not at all and the instrument 25 is so calibrated with the thermocouples as to produce a full scale deflection under such conditions. It will now be seen that, with proper calibration, instrument 25 produces a deflection from zero to full scale as brush 31 moves from brush 30 about the disk to the 180 degree point, and produces a straight line proportionate deflection for any intermediate position of brush 31. It remains only to move brush 31 from brush 30 in proportion to some change or measurement to be transmitted and such change or measurement will be indicated by instrument 25. It will, of course, be evident that brush 31 may be moved by hand but it will generally be preferable to move it automatically in response to the condition or measurement to be transmitted.

Figs. 2 and 3 show one way in which this may be done automatically and also other details of construction of the transmitter. As shown in Fig. 3, the shaft 28 of the transmitter is driven through suitable reduction gearing 33 by a small constant-speed motor 34. The disk 10 of Fig. 1 is secured to shaft 28 and is made of a central insulating layer 27a and outer segmental conducting layers 26a and 26b suitably clamped together. The two conducting segments are electrically connected together by the shaft 28 and through a slip ring 35 to the brush 29 to one side of the telemetering circuit 11. The stationary brush 30 overlaps conducting segment 26a and a portion of the circular insulating disk 27a. The movable brush 31 overlaps conducting segment 26b and a portion of the insulating disk 27a. By this arrangement, brush 31 may be moved adjacent and in line with brush 30 without interference and also the brushes are maintained in their radial positions, moving smoothly on and off the conducting segments as the disk rotates.

The movable brush 31 is supported on an arm 36 that is arranged to be adjusted about shaft 28 in response to the measurement to be transmitted. In this case, the device is arranged to transmit an indication of water level, and arm 36 is secured to a drum 37 about which is wound a cable 38 connected at one end to the float 39 and at the other end to a weight 40. The drum is free to turn on an extension of shaft 28. Its arm 36 is suitably insulated from the shaft and is connected through the flexible cable 32 in parallel with stationary brush 30 to the other side of the telemetering circuit 11. It will be evident now that the brush 31 will be rotated away from brush 30 as the water level at 41 rises. The instrument 25, Fig. 1, may then be calibrated to indicate water level or such other variable condition as may be caused to rotate movable brush arm 36.

The transmitting system is capable of considerable flexibility. For example, it will be observed in Fig. 1 that it is immaterial which way the movable brush 31 is moved about the commutator from the stationary brush 30 and, for some telemetering purposes, it may have a range of move-

ment each way from the stationary brush. Also, this transmitter may have both brushes movable to transmit a signal corresponding to the sum or to the difference of two variables. For instance, if in Fig. 1 the zero transmitting positions of both brushes are at the point occupied by brush 30 and we give brush 31 a range of movement from this point ninety degrees in a clockwise direction in accordance with one variable and we give brush 30 a range of movement from this same point ninety degrees in a counterclockwise direction in accordance with another variable, the transmission impulses will vary in the same way as before but in accordance with the sum of the two variables. If both brushes are movable in the same direction from the same zero-transmitting point in accordance with two variables, the transmission impulses will vary in the same way as before but in accordance with the difference of the two variables. The range of movement of the brushes in this case may be 180 degrees. No change is required in the receiving apparatus when the transmitter is used to transmit the sum or difference of two variables.

The transmitter may be arranged to transmit two or more variables without correspondingly duplicating all of its parts as will be explained in connection with Fig. 4.

The receiver may produce an integrating measurement, a number of receiving relays may be connected in series or in parallel and be located at different receiving points, separate sources of supply may be used for the telemetering relay circuit and for the receiving apparatus, as will be explained in connection with Fig. 4, and it will be obvious that the telemetering channel may be of the carrier-current type if desired.

In Fig. 4, there is included a system such as has already been described in connection with Fig. 1 and the similar parts are designated by like reference characters.

The rotary transmitting disk 10 is provided with an extra set of stationary and movable brushes 43 and 44, respectively, for transmitting a second measurement. As shown, these extra brushes utilize that half of the periphery not occupied by the brushes 30 and 31. It will be evident, however, that, if we provide spaced apart conducting segments and an arrangement of brushes that may be shifted past each other, as exemplified in Figs. 2 and 3, any desired number of sets of stationary and adjustable brushes may be provided to transmit a corresponding number of different measurements simultaneously. It will be evident that, in Fig. 4, the brushes 43 and 44 may be used to transmit one measurement while the brush set 30 and 31 is transmitting some independent measurement. The two transmitting channels use the same source of supply 13 and the common transmitting wire leading to brush 29.

The receiving relay 45 is similar to the relay 12 already described except that it has a double set of contacts. However, one of the receivers controlled by relay 45 is arranged to integrate the measurement received. In this case, the receiver comprises a pair of similar motors such as similar self-starting synchronous motors 46 and 47 having their rotors connected to the same shaft 48, driving a common counter 49. The motors, when energized, operate in opposite directions. They are supplied from a common alternating-current source 50 through the upper set of contacts of relay 45, and due to the operation of the relay 45, the motors are energized alternately as the

relay is energized and deenergized. As shown, the relay is energized and motor 47 is energized through the upper relay contact. Motor 47 drives register 49 in the forward direction and it will be noted from the position of movable brush 44, which is about 90 degrees removed from its companion stationary brush 43, that the transmitted measurement is about half way between zero and maximum value and that motor 47 will drive register 49 forward approximately three-fourths of the time and motor 46 will drive it in the reverse direction approximately one-fourth of the time during each cycle. The average result is that register 49 is advanced by an amount proportional to the displacement of brush 44 from brush 43. When the brushes 43 and 44 are together, the average advance of register 49 per cycle will be zero. When the brushes are displaced 180 degrees, register 49 will be advanced continuously. Since the two motors 46 and 47 have the same speed, have similar starting and stopping characteristics, and are energized by a common constant-frequency source, accurate integration over appreciable time periods results.

It will be evident that, if relay 45 were connected in series with relay 12 and brushes 30 and 31, meter 25 would produce an indication and register 49 an integration of the same measurement. In this case, the brushes 43 and 44 could be used for transmitting some other measurement to an additional relay. I have shown another receiving relay 51 connected in series with relay 12, the relays 12 and 51 being assumed to be located at different receiving points. The relay 51 controls a somewhat different type of differential-measuring apparatus. When the relay is energized, a charging circuit from a source 52 is closed to a condenser 53. When the relay is deenergized, a discharge circuit for the condenser is closed through a resistance 54. A suppressed-zero heavily-damped millivoltmeter 55 is connected across the condenser and measures the average charge thereof. The average charge on the condenser will be proportional to the difference between the charging and discharging times and, by suitably proportioning the capacity of the condenser and the discharge resistance, accurate measurements proportional to the quantity transmitted will result.

At 56 is another series-connected relay controlling a heater circuit like that controlled by relay 12. However, the thermocouples 21 and 22 are connected in series-opposition to a single-coil millivoltmeter 57, which is less expensive than the double-coil differential instrument 25. The differential function occurs in the series thermocouple circuit which sends a current through the instrument 57 proportional to the difference of the voltages of the two thermocouples.

The relay 45, which controls the integrating register 49, is provided with an extra contactor 58 for controlling an indicator receiver like that controlled by relay 56. Thus the measurement transmitted from contacts 43 and 44 is integrated and indicated at the receiving station or stations.

It will be noted that the impulses sent out from the transmitter occur periodically, for example, once per second, although the duration of each impulse may vary in accordance with some variable being transmitted. I may, therefore, utilize the timing function which is inherent in the constant impulse rate to operate impulse-timing devices at any place where such impulses are received. This will be found useful for the driving of recording charts, operating of time switches,

for establishing the resetting interval of time meters, for indicating time, etc. At 60, in Fig. 4, I have indicated a timing device of the impulse type operated by relay 45. Impulses are received by the relay 45 once per second in the system as previously described and the plunger of the relay may operate a simple ratchet mechanism in the clock once per second, which mechanism is then geared to the clock hands or other timing mechanism in the proper relation to indicate time. Where timing devices are operated off of the impulse telemetering circuit, it will be advisable to limit the displacement of the brushes 43 and 44 to slightly less than 180 degrees so that there will never be a condition where the circuit is continuously energized as in the case of exact 180 degree displacement of the brushes. This is of no particular disadvantage with respect to the telemetering system because it is only necessary to limit the displacement of the brushes by a few degrees less than 180 in order to always transmit time impulses. When used for this purpose, the transmitter serves in addition as a master clock.

In accordance with the provisions of the patent statutes, I have described the principle of operation of my invention together with the apparatus which I now consider to represent the best embodiment thereof but I desire to have it understood that the apparatus shown is only illustrative and that the invention may be carried out by other means.

What I claim is new and desire to secure by Letters Patent of the United States:

1. A telemetering system comprising, a transmitter, a telemetering circuit, receiving apparatus, and a source of supply for the telemetering circuit and receiving apparatus, the transmitter comprising means for opening and closing the telemetering circuit and repeating such opening and closing cycle continuously at a constant rate together with means for progressively varying the opening and closing period relation per cycle from a relation where these periods are equal to a relation where the open period is reduced to zero and the closing period is increased to the full time of the cycle, the receiving apparatus comprising a relay which is energized and deenergized in accordance with the circuit-closing and opening operations of the transmitter, and differential electrical measuring means having opposing energizing circuits respectively energized through said relay as the relay is energized and deenergized for producing a measurement proportional to the difference between the time the relay is energized and the time it is deenergized.

2. In a telemetering system, a transmitter comprising a rotary commutator having a conducting surface extending over an arc of 180 degrees, a pair of relatively adjustable brushes positioned to make contact with said conducting surface as the commutator is rotated, means for rotating said commutator at constant speed, and a telemetering circuit including a source of supply, one side of said circuit being connected to said conducting surface and the other side being connected in parallel to said brushes whereby the circuit is closed by said transmitter periodically for a time which varies with the relative spacing of said brushes.

3. In a telemetering system, a transmitter comprising a commutator having conducting and insulating segments each extending over different 180 degree portions of the commutating surface, a pair of relatively movable brushes bearing on

said commutator, a telemetering circuit including a source of supply, said brushes being connected in parallel to one side of said circuit and the conducting segment of the commutator being connected to the other side of said circuit, means for driving said commutator at a constant speed, means for controlling the spacing of said brushes about the commutator in response to the summation of two variables, and receiving 10 apparatus associated with said circuit and responsive to the impulses transmitted thereover for producing a measurement corresponding to the relative spacing of said brushes.

4. In a telemetering system, a receiver comprising a double-throw switch, a relay for operating said switch which, when energized, moves the switch to one position and, when deenergized, moves the switch to the other position, a source 15 of supply, a pair of heater circuits alternately energized from said source through said two-way switch as the relay is energized and deenergized, a thermocouple associated with each heater circuit so as to respond to the heat generated, and a measuring instrument connected to said thermocouples so as to be responsive to the difference 20 in heating in the two heater circuits.

5. In a telemetering system, a transmitter comprising a commutator having a conducting segment extending over 180 degrees of its commutating 25 surface and an insulating segment extending over the remaining portion of its commutating surface, a stationary contact bearing on said surface, a movable contact bearing on said surface, means responsive to a variable to be transmitted 30 for moving the movable contact about the commutator away from and towards the stationary contact as the variable increases and decreases respectively, a telemetering circuit including a source of supply, means connecting said contacts in parallel to one side of said circuit and the conducting segment of the commutator to the other side of said circuit, and means for rotating 35 said commutator at a constant speed.

6. In a telemetering system, a transmitter com-

prising a commutator device for periodically transmitting current impulses varying in duration from 50 per cent to slightly less than 100 per cent of the time of the periodic transmitting cycle, a receiver responsive to the duration of such impulses in terms of said variable, a timing device operated by said receiver and responsive to the frequency but not the duration of such impulses, and a communicating channel between said transmitter and receiver.

7. In a telemetering system, a transmitter comprising a commutating device having a part rotated at constant speed and a plurality of pairs of brushes bearing on said rotating part, the brushes of a pair being relatively adjustable 1 with respect to each other about said rotating part, the rotating part having a conducting segment which extends over an arc of about 180 degrees such that it makes contact with a brush through one-half of each revolution, said device 2 serving to transmit periodic current impulses over each pair of brushes, the duration of an impulse varying with the displacement of the pair of brushes through which it is transmitted, the brushes of one pair being adjustable independently of the adjustment of the brushes of a different pair.

8. A telemetering system comprising a transmitter having means for periodically transmitting current impulses and varying the duration of such impulses over a range between 50 and nearly 100 per cent of the duration of the impulse cycle of such transmitter in response to a variable to be transmitted, a communicating channel over which such impulses are transmitted including a relay 35 device responsive thereto, means controlled by said relay in response to the difference in the time duration of such impulses and the time duration remaining in the impulse cycle for measuring such difference in terms of the variable transmitted, and a timing device operated by said relay in accordance with the rate at which such impulses are transmitted.

CLYDE E. STEWART.
